RECORDING SYSTEM FOR TELEPHONE CONVERSATIONS

Herman S. Heller, West Los Angeles, Calif.

Application November 8, 1937, Serial No. 173,302

4 Claims. (CL. 179—6)

This invention relates generally to systems for recording telephone conversations, and deals particularly with systems for recordation of telephone conversations without making electrical connection to the telephone system.

It is well known that telephone companies prohibit electrical connection of any type of recording equipment to the telephone system, the purpose of this rule being to prevent interference with normal telephone operation or service.

It is accordingly a primary object of the invention to provide an improved system for recording both sides of a telephone conversation without establishing electrical connection with the telephone equipment.

In accordance with the present invention, there is provided an acoustic coupling instrument adapted to be related in acoustic relation to the standard telephone set of the commercial telephone system. In a preferred form of the invention, the usual telephone instrument of the main telephone system is simply rested on the acoustic coupling instrument, the transmitter and receiver of the telephone instrument being supported in acoustic coupling relation to a speaker and microphone, respectively, of the coupling instrument. The microphone of the coupling instrument picks up the sound reproduced by the telephone receiver, and produces a voice current, which is suitably amplified, and then conducted to the receiver of an auxiliary telephone which is used by the person operating the system. The voice current produced by talking into the transmitter of this auxiliary telephone is suitably amplified and then conducted to the speaker of the acoustic coupling instrument, where the sound spoken into the auxiliary telephone is audibly reproduced, and picked up by the transmitter of the telephone connected to the main telephone system. A recording system is provided for making a record of both the voice current conducted to the receiver of the auxiliary telephone instrument, and the voice current conducted to the speaker of the acoustic coupling device. It will be evident that both sides of the telephone conversation will thereby be recorded. When the system is not being used, the auxiliary telephone instrument is rested on the acoustic coupler device, and at such time the main telephone instrument rests on its usual telephone stand. The telephone instrument may be used at any time, without making a recording, in the normal manner.

An optional feature of the present invention comprises means automatically actuated as the

auxiliary telephone instrument is lifted from the acoustic coupling instrument, prior to placement of the main telephone instrument thereon, for setting the recording system and amplifiers in operation.

The invention will be best understood by referring now to the following detailed description of a present preferred embodiment thereof, reference for this purpose being had to the accompanying drawings, in which:

Fig. 1 is an elevational view of the acoustic coupler of the present invention in a form adapted for use in connection with a telephone instrument of the "French" type;

Fig. 2 is a vertical longitudinal sectional view of the device of Fig. 1, with the auxiliary telephone instrument rested thereon;

Fig. 3 is a view like that of Fig. 2, but with the main telephone instrument rested thereon; and

Fig. 4 is a schematic diagram of the electrical system of the present invention.

Numeral 10 designates generally a usual commercial telephone instrument of the "French" type, though it will be understood that the present invention may be adapted to other types of telephone instruments, the invention being here illustrated in its specific adaptation to use in association with a "French" 'phone since that type of 'phone is now in wide use, though without implication of any necessary limitation thereto.

The usual stand for telephone instrument 10 is indicated at 11, the connecting cable being indicated at 12. The cable 13 leading from stand 11 will be understood to be connected to the usual main or commercial telephone system. Telephone instrument 10, which will hereinafter be referred to as the main telephone, is here shown as of a well known type embodying ear piece or receiver 14 and transmitter or microphone 15, connected by a handle 16.

The acoustic coupler 17 of the present invention is shown in a typical form in Figs. 1, 2 and 3, embodying a somewhat elongated body or stand 18 having a base comprising an outwardly turned flange portion 19 and a removable cover plate 20 and instrument supporting plate 21 secured thereto in any suitable removable manner.

Opposite ends of body 18 are formed with openings 24 and 25 spaced apart and positioned properly to receive the transmitter 15 and receiver or ear piece 14, respectively, of telephone instrument 10 (see Fig. 3). Opening 24 is defined by a rim 26 on which is fitted a

coupler ring 27, preferably of resilient material as rubber. This ring 27 is formed with an internal upwardly facing shoulder 28 and a tapered inner wall surface 29 above shoulder 28, adapted to receive the end portion of the transmitter with a noise-excluding fit. Thus, the transmitter is shown with an annular shoulder 30 resting on ring shoulder 28, and with its outer portion 31 fitting within ring surface 29.

10 Body opening 25 is provided with a somewhat similar rim 35 on which is fitted a coupler ring 36, also of resilient material such as rubber, and provided with an internal upwardly facing shoulder 37 and a tapered inner wall surface 38 above shoulder 37, adapted to receive the end portion of the receiver or ear piece 14 of the telephone instrument with a noise-excluding fit. Receiver 14 is shown provided with a shoulder 39 resting on ring shoulder 37, and with its outer rim portion 40 fitting within ring surface 38.

20 A speaker S is removably supported by a mounting 32 and a spring bracket 33 on plate 21, so that an annular flange 34 formed on its horn 41 is supported against a shoulder 42 surrounding a sound passage 43 leading to an acoustic chamber 44 between the mouth or horn of the speaker and the transmitter 15 of telephone 10. Preferably, a resilient ring 45, for instance of rubber, is placed between flange 34 and shoulder 30 42, so as to exclude noise from chamber 44.

25 A microphone M is removably supported by a spring bracket 46 mounted on plate 21 against a shoulder 47 formed around passage 48 leading to acoustic chamber 49, between receiver 14 of telephone 10 and said microphone M, a resilient ring 47a, for instance of rubber, being preferably placed between the microphone and shoulder 47, so as to exclude noise from chamber 49.

30 Mounted on body 18, between openings 24 and 40 25, is a positioning device 50, similar to that used on a conventional "French" telephone instrument, said device 50 having four upwardly extending prongs 51 adapted to receive the handle 16 of main telephone instrument 10 when 45 placed on the coupler (see Fig. 3).

35 Fig. 2 shows a second or auxiliary telephone instrument 86 rested on the acoustic coupler instrument. This second telephone 86 has a handle 86a provided on its underside with a lug or ridge 86b, not present on standard instrument 10, and when instrument 86 is placed on the coupler, ridge 86b engages and depresses a plate 52 mounted on the upper end of a vertical plunger 53 slidably mounted in a bore 55 extending 50 through supporting member 56 and downwardly within a depending extension 56 on member 56. Plate 52 and plunger 53 are normally supported in an uppermost position by a coil spring 57 placed below plunger 53 and seating at the bottom on a shoulder 58 forming the juncture between bore 54 and a reduced bore 59 extending through the lower end of projection 56. Upward movement of plunger 53 and plate 52 is limited by engagement of a cross pin 60 in the 55 lower end of a reduced plunger portion 61 extending downwardly through bore 59. The screwthreaded lower extremity of projection 56 extends downwardly through an opening 62 in a web 63 extending transversely across the hollow 60 interior of body 18, and a nut 64 screwthreaded on said lower extremity secures supporting device 50 tightly to the body.

65 A switch 66, here typically shown as comprising switch arms 67 and 68 having cooperating contacts, as illustrated, is mounted on a support

70 ing bracket 70 secured to the underside of web 63. When plunger 53 and plate 52 are in uppermost position, when telephone instrument 86 is not mounted on the device, switch arm 67 stands in a position with its contact in engagement with the contact of switch arm 68. When telephone instrument 86 is mounted on the device, handle rib 86b engages the plate 52 and depresses said plate 52 and plunger 53 against spring 57 to the position illustrated in Fig. 2, 10 causing stem 61 to be moved against a cam element 73 on switch arm 67 and to cam said arm 67 away from switch arm 68 to separate their respective contacts. The act of removing telephone 86 from its position of rest on the coupler device thus allows stem 61 to rise and the contacts on arms 67 and 68 to make. When main telephone 10 is placed on the coupler, its handle clears plate 52, and switch 66 remains closed.

15 Reference is now directed to Fig. 4, showing a typical form of the electrical and recording system of the invention.

20 The aforementioned microphone M of the acoustic coupling instrument is connected by conductors 80 and 81 to the input side of an amplifier 82, which may be typically of the vacuum tube type. The output leads 83 and 84 of amplifier 82 are connected to the receiver 85 of an auxiliary telephone instrument 86. The transmitter 88 of telephone instrument 86 is connected by leads 89 and 90 to the input side of an amplifier 91, which may also be of the vacuum tube type, the output leads 93 and 92 of which are connected to the speaker unit S of the acoustic coupler device. It will of course be understood by those skilled in the art that amplifiers 82 and 91 may be combined within one unit as a dual channel amplifier, if desired.

25 A recording system is provided, and while this may be of any suitable or well known type, I have here typically and conventionally indicated a recording system of the magnetic type. Thus a magnetic recording element 96, wire or tape, is indicated as being moved from a supply reel 97 to a take-up reel 98, the latter being conventionally indicated as driven by an electric motor 99. Motor 99 will of course be understood as driving tape 96 and take-up reel 98 through any suitable or usual driving gear, not necessary to illustrate in detail herein. Tape 96 is shown as passing first through a pair of erasing coils 102 potentiometered by a battery 103 in a circuit 104 connected to said coils. These erasing coils magnetically prepare the tape to receive the magnetic record, and as typical of various magnetic recording methods, the erasing coils may be considered as magnetizing the tape to saturation. The tape passes next between recording coils 106, placed on opposite sides of the tape, and these recording coils are connected in circuit so as to carry voice currents corresponding to both sides of the telephone conversation. Thus, coils 106 are shown as connected by leads 107 and 108 across a pair of leads 109 and 110, leads 109 and 110 being connected across output leads 83 and 84 of amplifier 82, and also being connected across output leads 92 and 93 of amplifier 91. Thus, a portion of the voice current output of amplifier 82, and a portion of the voice current output of amplifier 91, are recorded on magnetic tape 96.

30 The described electric switch 66, which will be understood to be closed while telephone unit 10 is mounted on the acoustic coupling device, closes a relay circuit 120, including a battery 121, energizing a relay 122, to close the power supply cir-

cuit energizing the amplifiers and driving the magnetic recording system. Thus, relay 122 when energized by closure of switch 66, closes an electrical circuit between contacts 123 and 124 in power supply lead 125, and also forms an electrical connection between contacts 126 and 127 in power supply lead 128. Power supply leads 125 and 128 are diagrammatically and conventionally indicated as having a pair of branch leads 130 and 131 energizing electric drive motor 99, and as having another pair of branch leads 132 and 133 supplying power to amplifiers 82 and 91.

Relay 122 is shown as also closing the circuit energizing erasing coils 102, being provided with a pair of contacts 134 and 135 included in circuit 104, which are closed by the relay at the same time the power supply leads are closed.

The telephone instrument 10 may of course be used in its normal manner, entirely independently of the recording system of the present invention. Telephone instrument 86 normally rests on the acoustic coupler, holding control switch 66 open. When it is desired to make a recording of a telephone conversation, telephone instrument 86 is lifted from the acoustic coupling device, allowing switch 66 to close automatically, thereby effecting energization of amplifiers 82 and 91, as well as setting the recording system in operation. Telephone instrument 10 is then placed at once on the acoustic coupler, and telephone instrument 86 is picked up and used in an ordinary manner. Speech audibly reproduced within acoustic chamber 49 by the receiver 14 of telephone instrument 10 is picked up by microphone M, the resulting voice or telephone current being conducted to amplifier 82, and after amplification, being audibly reproduced by receiver 85 of telephone instrument 86, as well as being recorded on magnetic tape 96. Similarly, the voice or telephone current resulting from a speech input into transmitter 88 is amplified at 91, and after amplification is audibly reproduced by speaker S within acoustic chamber 48, as well as recorded on magnetic tape 96, the resulting audible reproduction produced by speaker S being picked up by transmitter 15 and converted to a voice current in the main telephone system. The rubber mounts 27 and 36 of the acoustic coupler exclude all external noise, and conversation is uninterfered with by the interposition of the system of the present invention. Amplifiers 82 and 91 are of course adjusted to provide such a gain as will result in acoustic reproduction at receiver 85 and speaker S of such a volume as will afford reproduced sound of normal volume from receiver 85, and a speech input to transmitter 15 of normal loudness, and such as will at the same time provide voice currents of suitable amplitude for proper recording on tape 96.

When the conversation is completed, telephone instrument 10 is replaced on its stand 11, and telephone instrument 86 is replaced on the acoustic coupler, thereby stopping the recording means and opening the circuit to the amplifiers.

It will be understood that various changes in design, structure, and arrangements of the electrical systems, may be made without departing from the spirit and scope of the invention or of the appended claims.

I claim:

1. In a system for recording a telephone conversation, the combination, with a telephone instrument of a main telephone system, of an acoustic coupler comprising a microphone and

speaker adapted to be acoustically coupled to the receiver and transmitter, respectively, of said telephone instrument, an auxiliary telephone instrument, having a receiver and a transmitter, electronic amplifier means for amplifying the telephone currents produced by the transmitter of said auxiliary telephone instrument and the microphone of the acoustic coupler, an amplifier output circuit carrying the amplified auxiliary telephone transmitter currents connected to the speaker of said acoustic coupler, another amplifier output circuit carrying the amplified coupler microphone currents connected to the receiver of the auxiliary telephone, and sound recording means having an input circuit associated with 15 and receiving electrical energy from each of said amplifier output circuits.

2. In a system for recording a telephone conversation, the combination, with a telephone instrument of a main telephone system, of an acoustic coupler comprising a stand adapted to removably support a telephone instrument, and a microphone and speaker positioned on said stand in such manner as to be acoustically coupled to the receiver and transmitter of a telephone instrument when said telephone instrument is supported in operative position on said stand, an auxiliary telephone instrument, said last mentioned instrument adapted to be rested on said acoustic coupler when the recording system is not in use, a normally closed switch on said coupler, switch operating means unaffected by the main telephone instrument when mounted on said coupler, means on the auxiliary telephone instrument acting when said instrument is positioned on the coupler to engage and operate said switch operating means to hold said switch in open position, electric circuiting for conducting telephone currents between the microphone of the acoustic coupler and the receiver of the auxiliary telephone instrument, and between the transmitter of the auxiliary telephone instrument and the speaker of the acoustic coupler, sound recording means for making sound records of said telephone currents, and an electrical circuit for controlling starting and stopping of said sound recording means controlled by said switch on said acoustic coupler, so as to automatically start said recording means when said auxiliary telephone instrument is removed from its position of rest on the stand of said acoustic coupler.

3. In a system for recording a telephone conversation, the combination, with a telephone instrument of a main telephone system, of an acoustic coupler comprising a stand adapted to removably support a telephone instrument, and a microphone and speaker positioned on said stand in such manner as to be acoustically coupled to the receiver and transmitter of a telephone instrument when said telephone instrument is supported in operative position on said stand, an auxiliary telephone instrument, said auxiliary telephone instrument being adapted to be rested, when the system is not in use, on said acoustic coupler stand, electric circuiting for conducting telephone currents between the microphone of the acoustic coupler and the receiver of the auxiliary telephone instrument, and between the transmitter of the auxiliary telephone instrument and the speaker of the acoustic coupler, sound recording means for making a sound record of said telephone currents, and means for automatically setting said sound recording means into operation by virtue of removing said auxili- 75

ary telephone instrument from the stand of said acoustic coupler.

4. An acoustic coupler, comprising a hollow body having a transmitter opening and a receiver opening spaced apart by a distance equal to the spacing between the transmitter and receiver of a telephone instrument, said openings leading from acoustic chambers within said body, resilient mounting rings around said openings adapt-

ed to receive and support the transmitter and receiver, respectively, of a telephone instrument in noise excluding relation, and a speaker and a microphone positioned within said body in communication with the acoustic chambers leading to the transmitter and receiver openings, respectively.

HERMAN S. HELLER.
